UNITED STATES PATENT OFFICE.

THOMAS C. BALL, OF KEENE, NEW HAMPSHIRE, ASSIGNOR TO HIMSELF, L. BISCO, A. S. DAVIS, K. CROSSFIELD, EDW. EDWARDS, AND JACOB GREEN, ALL OF SAME PLACE.

RAILROAD-CAR WHEEL.

Specification of Letters Patent No. 22,049, dated November 9, 1858.

To all whom it may concern:

Be it known that I, THOMAS C. BALL, of Keene, in the county of Cheshire and State of New Hampshire, have invented a new and useful Improvement in Car-Wheels; and I do hereby declare that the following is a full, clear, and exact description thereof, reference being had to the accompanying drawings, making a part of this specification.

- 10 The nature of my invention consists in a mode of constructing a car-wheel in two principal parts, one of which is secured to the axle and forms the center or body of the wheel. The other is a rim, which constitutes 15 the outer part or tread of the wheel. This encircles the center part, a small space being left between them forming a thin annular chamber which is packed with india-rubber or other elastic material.
- 20 The wheels of cars in rapid motion occasion severe concussions by coming in contact with inequalities of the track, especially at the ends or joints of the rails, producing injurious effects, by straining and breaking the 25 axles and other parts of the running gear of the cars, also battering and abrading the rails. The elastic packing which is interposed between the center and tread of this wheel, allows a slight yielding of its parts, 30 and operates to check the severity of the concussions or shocks, received by either part of the wheel by preventing their continuation from one part to the other, thereby diminishing the consequent injurious effects on 35 both the rails and the cars. Also there has always existed difficulties in casting perfect wheels with chilled rims, on account of the different shrinkage of the various parts in cooling, causing some places to become 40 strained or weakened, and oftentimes to break, sometimes causing disastrous accidents. This evil is entirely obviated by my mode of construction, as the chilled rim is cast separately from the body of the wheel, 45 and the form of each part is such that they may be cooled evenly and without the liability of becoming strained. Another useful object accomplished by this mode of construction is that, when the tread is worn out 50 it can easily be removed and replaced by a new one, thus making a saving of a large share of the expense involved in exchanging an entire wheel as ordinarily constructed.

Having thus explained the nature and ob-

ject of my invention I will proceed to describe the mode of construction.

Figure 1, of the drawings, represents a side view, and Fig. 2, a cross-section of the wheels. Fig. 3, is a portion of the chamber between the body and rim of the wheel, 60 which contains the elastic packing. Fig. 4, shows the form of the plate or web of the outer rim, between the tread and the annular chamber.

A, is the center part, or body. It is made 65 in a form to possess great strength and produce uniformity in cooling, by having a plate or web (of about equal thickness in all its parts,) which is strengthened by the slightly curved ribs *a, a, a, a*, which extend 70 from the hub to the edge on each side. Its periphery forms a part of the chamber for the elastic packing, and a flanch on one side, serves to protect one edge of the packing, and to assist in keeping the outer rim of the 75 wheel in its place.

B, is the outer part, or rim of the wheel. Its outer edge or periphery forms the tread of the wheel. It is provided with a flanch and is chilled in the usual manner. Its interior surface is made to correspond with the periphery of A, leaving a sufficient space between them for the elastic packing. A narrow rim or flanch M extends inward from one side, and confines the edge of the packing on the opposite side from the flanch on A. The metal forming the interior rim of B, and that of the tread is connected by a zigzag or serpentine plate or web, as shown 80 by Fig. 4. This form gives great strength 85 to the rim B, affording support almost the entire width of the tread; it also affords a disposition of the metal very favorable to uniformity in cooling, as it requires so much less thickness of metal in the web and inner rim, than it does in the tread or part which is chilled, that both may be cooled in about 90 the same time, and cause no material difference of shrinkage.

In packing a wheel I use "fibrous india-rubber packing" or other suitable material of a similar nature, taking a strip of the proper dimensions to fill the space intended to contain it. I wind it against one of the surfaces (of A, or B,) making a part of the 105 annular chamber, where it is intended to remain. Next to this is placed a strip of sheet metal for the surface of the other part

to slide against while they are being pressed together. This protects the elastic substance used for the packing, and prevents it from wrinkling. The center part is then 5 introduced into the rim, along with the elastic packing and its sheet metal protector. The periphery of A, and interior surface of B, which are next the packing are made sufficiently beveling, or conical, to facilitate the 10 insertion of one part within the other, and cause sufficient compression of the packing, (when they are driven together) so that it will sustain a proper amount of weight, and prevent undue looseness between the parts 15 of the wheel. The elastic substance is represented by the red in the drawings, marked, C, and the sheet metal protector by the black, marked D.

The parts A, and B, are secured together 20 by means of bolts E, E, E, E, a proper number of which may be used. They are arranged so as to vibrate sufficiently to compensate for the yielding of the elastic packing, allowing a slight diametrical motion of 25 the parts of the wheel, but prevents the rotation of one part independent of the other, should there be any tendency so to do. One end of each bolt catches on the inner rim of part, B, and passing through notches in its

flanch, and in the periphery of A, terminates 30 outside the flanch on A, being provided with two screw-nuts which are turned closely together to prevent their becoming loose and jarring off by the working of the bolts.

I do not claim as my invention to make 35 a car wheel in two parts, neither do I claim interposing rubber or other elastic material between the two parts, for any of the purposes herebefore described, but

I do claim (for a car wheel, with an insertion of rubber or other elastic substances 40 between the two parts)—

1. The making of the rim or tire and its flanch M, in one piece for the purpose of 45 strengthening each other.

2. I claim the mode of confining the two parts A and B, together, by means of the hook, or pivot bolts substantially as described or their equivalents, to prevent the wear and chafing of any stationary confinement also to be at liberty to make each bolt 50 do its share of labor assigned, for castings are most invariably too uneven to get any equality of confinement in other modes.

THOS. C. BALL.
